UNITED STATES PATENT OFFICE

ARNOLD H. FRANCIS, OF COLLEGEVILLE, PENNSYLVANIA

FLAG HOLDER

Application filed January 30, 1930. Serial No. 424,653.

This invention relates to holders or supports and is directed more particularly to a device for supporting a plurality of flags from a window.

5 The primary object of the present invention is to provide a flag holder which may be easily and quickly installed or removed from a window without the use of screws, nails or similar fastening elements and which when 10 installed shall securely hold a plurality of flags in a decorative display.

Another object is to provide a flag holder which shall be retained in position by the window sash and hence can be used in any 15 desired location without previous preparation.

A further object is to provide a flag holder of the above character which may also be used on a wall or other surface to hold a plurality of flags in decorative display.

A still further object is to provide a flag holder of this general character which shall be simple in construction, inexpensive to manufacture and which may be easily and 25 quickly installed or removed.

The foregoing and other objects and advantages will be realized as the description proceeds and will be pointed out in the appended claims.

30 In the drawing accompanying and forming part of this application:

Figure 1 is a perspective view of a flag holder constructed in accordance with my invention;

35 Figure 2 is vertical sectional view through the holder and a window sash showing the holder in position; and

Figure 3 is a side elevation showing the holder attached to a vertical surface such as a 40 wall.

A holder constructed in accordance with my invention is preferably formed from sheet metal and comprises a base 1 having an upwardly extending rear portion 2 and an upwardly and forwardly inclined front portion denoted generally at 3.

The base portion 1 is preferably of a width sufficient to receive the lower rail 4 of a window sash as shown in Figure 2, and said base 50 is also formed with substantially circular

apertures 5 from each of which radiate in axial alignment suitable slots 6 for a purpose to be referred to hereinafter.

The rear portion 2 is disposed at substantially right angles to the base portion and is 55 preferably formed with a rearwardly curved tab 7 so that the holder may be easily grasped when the window is raised to prevent the device from falling out of the window.

The front portion 3 is inclined at an angle 60 of substantially 45° with the base 1 and projects forwardly and upwardly. As shown in Figure 1, this front portion is preferably 65 formed with a contour of pleasing design and is provided with a plurality of sockets to receive the staffs of the flags to be displayed. Each socket is formed by depressing the upper portion of the metal into a semi-circular groove 10 while the intermediate portion of the metal is similarly depressed in a reverse direction as indicated at 11. The lower portion of the metal is depressed to define a transversely disposed and arcuate shaped depression 12 which defines a shoulder 13 70 with respect to the sockets. Suitable apertures 14 and 15 are formed at the upper and lower ends respectively of the intermediate portion of each socket so that a flag staff may be inserted therethrough and will seat in the aforementioned groove and abut against shoulder 13.

In order to strengthen the device, I preferably 75 form suitable channels or depressions 16 in the adjacent portions of the base 1 and front portion 3.

In use, a flag staff is inserted in each 80 socket as explained above and the device is then placed on the window sill and the window closed so that the lower rail of the sash will contact with the base 1 as shown in Figure 2. This will securely hold the display in position. When it is desired to remove it, the window is raised while the tab 7 is 85 grasped to keep the device from falling out of the window.

If it is desired to use the display on a wall or other surface, suitable headed fastening elements such as screws or nails are secured to the wall or other surface, and then the heads of these elements are passed through 90

apertures 5 and the elements are engaged in slots 6, thereby detachably connecting the holder to the wall or other surface.

Claims:—

5. A holder of the character set forth formed from a single piece of sheet metal and comprising a base portion adapted to receive the lower rail of a window sash, a rear upwardly extending portion adapted to engage said rail, and a forwardly and upwardly extending portion, said last mentioned portion having integrally formed means to hold a plurality of flags in display formation.
10. A holder of the character set forth formed from a single piece of sheet metal and comprising a base portion, a rear upwardly extending portion, and a forwardly and upwardly extending portion, said last mentioned portion having a plurality of sockets embossed therein to receive a plurality of flags in display formation.
15. A holder of the character set forth formed from a single piece of sheet metal and having a base portion, a rear upwardly extending portion and a forwardly and upwardly extending portion, said last mentioned portion being embossed to define a plurality of sockets for the reception of flag staffs, and depressed to define a transversely disposed shoulder adjacent said sockets.
20. A holder of the character set forth formed from a single piece of sheet metal and comprising a base portion, a second portion bent at substantially right angles to said base, and a third portion bent at substantially 45° to said base, said third portion being embossed in opposite directions to define a plurality of sockets, each adapted to receive a flag staff.
25. A holder of the character set forth comprising a base portion adapted to seat on a window sill and receive the lower rail of a window sash, a rear upwardly extending portion adapted to engage said rail, and a forwardly and upwardly extending portion, said forwardly and upwardly extending portion having a plurality of sockets formed by embossing the metal in opposite directions, said sockets being adapted to receive a plurality of flags in display formation.

In testimony whereof I affix my signature.

ARNOLD H. FRANCIS.
